INKSTAND

Filed June 23, 1925

2 Sheets-Sheet 2

Fig. 8.

UNITED STATES PATENT OFFICE.

HARRY CHILINGIRIAN, OF BRIDGEPORT, CONNECTICUT.

INKSTAND.

Application filed June 23, 1925. Serial No. 39,012.

To all whom it may concern:

Be it known that I, HARRY CHILINGIRIAN, a citizen of Armenia, residing at Bridgeport, county of Fairfield, State of Connecticut, have invented a new and useful Inkstand, of which the following is a specification.

This invention relates to a stand for placing on a table or desk to hold writing materials such as ink, pencils, pens, and writing paper, and has for an object to provide a device of this character which will be neat and attractive in appearance, will be simple in construction, and which has means for sealing the ink receptacles so that the ink will not dry up in these receptacles, and also will not be spilled during handling of the device or should it be overturned.

It is a further object of the invention to provide means for sealing these receptacles which may be easily and quickly operated to expose the ink for use or to seal the ink receptacle without soiling the fingers.

With the foregoing and other objects in view, I have devised the construction illustrated in the accompanying drawings forming a part of this specification, similar reference characters being employed throughout the various figures to indicate corresponding elements. In these drawings,

Fig. 1 is a perspective view showing the preferred form of my device.

Fig. 2 is a transverse section thereof substantially on line 2—2 of Fig. 3.

Fig. 3 is a longitudinal section substantially on line 3—3 of Fig. 2, showing the ink receptacle closed.

Fig. 4 is a transverse section substantially on line 4—4 of Fig. 3, showing the ink receptacle exposed for use.

Fig. 5 is a top plan view thereof with one ink receptacle exposed and the other closed.

Fig. 6 is a transverse section corresponding to Fig. 2 showing a slightly different operating means for closing the ink receptacles in a position to allow access to the receptacles.

Fig. 7 is a similar view to Fig. 6 showing the device in position to close the receptacles.

Fig. 8 is a view similar to Fig. 1 showing a perspective of a slightly different construction.

Fig. 9 is a transverse section of the same substantially on line 9—9 of Fig. 10. 55

Fig. 10 is a longitudinal section substantially on line 10—10 of Fig. 9, and

Fig. 11 is a perspective view of the combined cover for the front compartment and the rack for holding pens and pencils. 60

Referring to Figs. 1 to 7, the cabinet comprises a rear wall 10, end walls 11 and front wall 12. The front wall is preferably lower than the rear wall to give a neater appearance, to provide more space at the rear part of the cabinet and an open space at the front of the cabinet for a rack for pens and pencils. Intermediate the front and rear walls is a vertical partition 13 extending longitudinally in the cabinet and dividing the cabinet into front and rear sections. Vertical transverse partitions 14 are also provided to divide the lower part of the cabinet into separate compartments, to form supports 65

for the covers, and forward compartments, and also to form a rack for supporting pens and pencils. As shown the upper edges of 70

these walls are formed with recesses 15 forwardly of the partition 13 to hold pens and pencils. The opposite sides of these partitions and the end walls 11 are provided with guides for covers 16 for the compartment 17 75

at the front of the cabinet. These guides are preferably in the form of grooves 18 cut in the end walls 11 and the partitions 14 in 80

which the opposite ends of the covers 16 are mounted to slide. These grooves extend to the rear wall 10 so that the covers may be 85

slid back from the position over the forward compartments into the rear part of the cabinet as shown in Fig. 4.

Mounted in the compartments 17 are ink 90

receptacles 19 such as glass bottles having openings in the top wall. On the under side of the covers 16 are mounted closures 95

20 for these ink receptacles, and these closures may be of any suitable material such as cork, rubber or a suitable fibre. Means 100

is provided for lifting these receptacles to bring the necks thereof against the closures 105

and clamp them against the closure to seal the receptacles and thus prevent evaporation of the moisture of the ink or spilling should the cabinet be overturned, or during handling.

In Figs. 1 to 5 I have shown a supporting

bar 21 extending longitudinally of the cabinet and mounted on a threaded rod 22 carried by a panel 23 in the central portion of the front section of the cabinet. This rod 5 has a knurled head 24 for operating the rod, and the receptacles 19 are mounted on this bar 21. It will be apparent that by turning the rod the supporting bar 21 may be raised to clamp the necks of the bottles 10 against the closures 20 or lowered to remove them from the closures. After they are thus lowered the cover 16 may be slid rearwardly as indicated in Figs. 4 and 5, to expose the receptacles to give access to the ink. 15 For easy manipulation of the covers they are provided with a raised rib 25 on the front edge thereof to give an easy grip for the operator in drawing the cover forwardly to the closing position. 20 In Figs. 6 and 7, I have shown a slightly different mechanism for raising and lowering the supporting bar 21. In this form the bar is mounted on a rod 26 extending through the panel 23, but pivoted to its 25 upper end is a cam element 27 having an eccentrically arranged surface 28 and a handle 29 for operation. By swinging this handle to the vertical position shown in Fig. 6 the ink receptacles are lowered away from the closures 20, but by swinging it to the 30 position shown in Fig. 7 the eccentric surface 28 coacting with the top of the panel will lift the bar 21 and clamp the ink bottles against the closure. This device is a little 35 quicker and simpler in operation than the screw shown in Figs. 1 to 5, as it may be operated by a simple swinging movement of the handle.

In the rear part of the cabinet I provide 40 a longitudinal partition 30 forming the bottom of a compartment 31 for papers, pens or other articles, and this compartment is closed by a movable cover 32.

In Figs. 8 to 11, I have shown a slightly 45 different construction. This cabinet comprises the rear wall 10, end walls 11 and front wall 12, the same as in the first form. The vertical longitudinal partition 33 does not extend the entire height of the cabinet 50 so as to give a larger compartment 34 in the lower part of this cabinet. A longitudinal horizontal partition 35 between this partition 33 and the rear wall form bottoms of compartments in the upper part of the cabinet. 55 In the present construction the vertical transverse partitions 36 divide this part of the cabinet into three compartments 37 and 38. The end compartments 37 contain the ink receptacles or bottles 19, but in this 60 form they are stationary. The rear wall 10 and vertical partition 33 are provided with guides for sliding covers 39 for these two end compartments, these guides in the preferred construction taking the form of grooves 40 extending longitudinally of the

cabinet. Each cover carries a closure 41 for the ink receptacles, and this closure is mounted on a rod 42 threaded in a block 44 carried by the cover, so that by rotating this threaded rod the closure may be clamped 70 against the neck of the bottle or raised therefrom, as shown in Figs. 9 and 10. After raising the closure from the bottle the bottle may be exposed by sliding the cover laterally toward the center of the cabinet over the 75 central compartment 38.

The central compartment 38 is closed by a removable cover 45, and the front part 80 of the lower compartment 34 is closed by a removable cover 46. This cover carries vertical members 47 having notches or recesses 48 in their upper edges to provide racks for supporting pens and pencils, and they also provide suitable means for lifting the cover 46 to remove it from the cabinet and give 85 access to the compartment 34.

Having thus set forth the nature of my invention, what I claim is:

1. In a device of the character described, 90 walls forming a cabinet having a compartment, a retractable cover for the compartment, means for supporting an ink bottle in the compartment, and means on the cover for closing the bottle.

2. In a device of the character described, 95 walls forming a cabinet having a compartment, means for supporting an ink bottle in the compartment, a cover over the bottle mounted to slide from this position to give access to the bottle, a closure for the bottle 100 carried by the cover, and means for causing relative movements between the closure and the bottle to close and uncover the bottle.

3. In a device of the character described, 105 walls forming a cabinet having a compartment, a cover for the compartment, an ink receptacle in the compartment, means for mounting the cover so that it may be slid to and from a position over the receptacle, a closure on the under side of the cover for 110 the receptacle, and means for raising the receptacle and to retain it against said closure.

4. In a device of the character described, 115 front, rear and end walls forming a cabinet, a longitudinal upright partition between the front and rear walls dividing the cabinet into front and rear portions, ink receptacles mounted in the forward part of the cabinet, 120 covers over the receptacles and mounted to slide into the rear portion of the cabinet to expose said receptacles, closures for the receptacles mounted on the under sides of the covers, and means for raising and lowering 125 the receptacles to press them against the closures to close the receptacles and to allow access to the receptacles.

5. In a device of the character described, 130 front, rear and end walls forming a cabinet, a longitudinal upright partition between the

front and rear walls dividing the cabinet into front and rear portions, ink receptacles mounted in the forward part of the cabinet, covers over the receptacles and mounted to be moved to and from a position over the receptacles, closures for the receptacles mounted on the covers, a support for the receptacles, an intermediate panel, and means mounted on the panel for raising the support to press the receptacles against the closures to close them and to lower the support to allow access to the receptacles.

In testimony whereof I affix my signature.

HARRY CHILINGIRIAN.
